UNITED STATES PATENT OFFICE.

JONATHAN JENKINS, OF JENKINS, KENTUCKY, ASSIGNOR TO THE JEFFREY MANUFACTURING COMPANY, OF COLUMBUS, OHIO, A CORPORATION OF OHIO.

ATTACHMENT FOR COAL-CUTTING MACHINES.

1,247,407.

Specification of Letters Patent.

Patented Nov. 20, 1917.

Application filed June 20, 1913, Serial No. 774,885. Renewed November 20, 1915. Serial No. 62,639.

To all whom it may concern:

Be it known that I, JONATHAN JENKINS, a citizen of the United States, residing at Jenkins, in the county of Letcher and State 5 of Kentucky, have invented new and useful Improvements in Attachments for Coal-Cutting Machines, of which the following is a specification.

The present invention relates to improvements in that type of mining machines in which the coal cutting mechanism is supported on track wheels, the machine being supported on the mine track both while it is being transported from point to point in 10 the mine and while the cutting mechanism 15 engages the coal to form a kerf. In a machine of this character which is now in use, the cutting mechanism is mounted upon the wheel supported base frame or truck 20 so as to project horizontally beyond the lines of the truck and so as to swing laterally in relation to the truck across the longitudinal vertical planes of the track to effect the cutting of a horizontal kerf. The 25 object of my invention, briefly stated, is to provide improved means for effecting lateral movement of the cutting apparatus in a machine such as last referred to.

An embodiment of the invention is illustrated in the accompanying drawing, whereof:

Figure 1 is a front elevation of a coal cutting machine of the type specified, equipped with the improved attachment;

Fig. 2 is a plan view;

Figs. 3 and 4 are, respectively, a fragmental view, partly in front elevation and partly in central transverse section, and a fragmental plan view, showing a modification.

These figures are diagrammatic to a certain extent in that they disclose only the essential features of the invention, the sectioning in Fig. 3 being for the purpose of 45 showing the pivotal mounting of the bed-plate.

Referring more particularly to the drawing, 1 designates, generally, the truck of the machine, 2 the operating mechanism, or 50 machine proper, 3 the bed-plate whereon the operating mechanism is mounted, and 4 the cutting mechanism. All of these instrumentalities are of conventional construction, and for that reason specific description 55 and illustration thereof are omitted.

However, it may be stated that the bed-plate 3 has an approximately central pivotal connection 33 with the floor or frame 5 of the truck, as shown in Figs. 2 and 3 which permits it to turn or swing in a horizontal 60 plane in either direction, and that the cutting mechanism 4 is of the endless chain type and is driven in any desired manner from the operating mechanism 2, the latter including a suitable motor. The chain is 65 indicated in Fig. 1, but is omitted from Fig. 2, and it operates in the usual manner when driven, to form the horizontal kerfs in the breast of coal, the rear end of the arm 6 which supports the chain being rigidly 70 connected with the bed-plate, so as to turn or swing therewith. In Fig. 2 the operating mechanism includes the parts whose positions are conventionally indicated by the rectangles adjacent to the numeral 2, the position at the left being that occupied by such translating devices as the builder sees fit to use, such as an armature and field magnet of any suitable sort, and the position at the right of said numeral 2 being that occupied 80 by the principal parts of the power transmitter. And the drawing is merely conventional in this respect, as numerous forms of operating mechanisms and motors, and numerous styles of connections are well 85 understood by mining machine builders. The truck is designed to travel along a suitable track 7, its propulsion being effected through the agency of the motor.

The machine may be braced, if desired, 90 and held stationary during working by means of a pair of jacks 8 and 9, both jacks being of conventional construction and being operated by the usual hand-wheels. In the present instance, the lower or side jack 95 8 has a universal-joint connection 10 with the truck floor 5, while the upper, or roof jack 9 is arranged at the opposite side of the truck from the jack 8, and rests at its lower end on the forked outer end 12 of a 100 supporting bracket 13, this bracket constituting the main element of the hereinafter-described feeding attachment. In the construction shown in Fig. 1, the two bracket members have direct pivotal connections 14 and 15 at their inner ends with a corner plate 16 mounted on the truck floor 5 and the adjacent end of a drop frame or plate 17 secured to the running gear, while in the modification represented in Figs. 3 and 4 110

the corner plate and the end of the frame are extended or elongated, as indicated by the numerals 18 and 19, the latter construction permitting the cutting mechanism to 5 swing through a greater arc. The bracket, in its operative position, projects at right angles to the side of the truck, as shown in full lines in Figs. 2, 3 and 4, but may be moved on entering or leaving the mine, 10 into a position in which it extends either directly in front of the truck, or rearwardly along the side thereof, as indicated in dotted lines in Figs. 2 and 4, the afore-mentioned parts 18 and 19 enabling the bracket 15 to clear the adjacent truck wheels. The connection 10 between the lower jack 8 and the truck floor likewise permits a swinging movement of that jack into and out of operative position. To hold the bracket 13 in 20 operative position, there is preferably employed a second pin or bolt 20 which is removably inserted through registering openings in the upper bracket member and the corner plate, (and, where the short plate 16 25 is used, an additional opening in the truck floor).

The afore-mentioned swinging or turning movement of the bed frame 3 is effected by means of the following devices. 21 is a 30 winding drum mounted on a shaft 22 which is driven through suitable connections by the operating mechanism 2. A rope or cable 23 has one end secured to the winding drum 21 and is arranged to pass over a guide pulley 35 24 the frame of which has a swiveled or caster-like mounting in a sleeve 29 carried by a bracket 30 on a base 28 which carries the operating mechanism and the cutting mechanism.

40 The cable 23, after passing over the guide pulley 24, is adapted to be extended laterally and connected with the outer end of the bracket arm 13 so that the latter may constitute an abutment to sustain the draft of 45 the cable when the drum 21 is rotated, thereby causing the bed plate 3 and the parts mounted thereon to swing laterally as will readily be understood. The cable 23 may be connected with the outer end of the bracket 50 arm 13 in any suitable manner but I prefer to arrange a guide pulley 25 between the arms of the forked end 12 of the bracket arm, the pulley being mounted on an upright pin 11. The cable is then provided at its 55 free end with an eye 26 adapted for detachable engagement with a hook 27 on the base 28. By doubling the cable back in the manner described, it will be understood that the stress on the cable is correspondingly lessened and for this reason I prefer this form 60 of construction.

In operation the machine, with the bracket arm 13 swung forward or rearward (according as the construction used is that shown 65 in Figs. 1 and 2, or that shown in Figs. 3

and 4), moves over the mine track to the end of the entry to be extended or up to the room face to be cut, the track extending longitudinally toward the said face. With the machine at the face, the first operation is the 70 making of the entering or sumping cut. My present improvements do not relate to this sumping cut and it need only be stated in passing that to effect the sumping cut the bed plate 3 is swung to the right until the 75 forward end of the cutter frame 6 is at the right rib. Thereupon, the parts being now held against swinging, the cable 23 is carried forward to a point adjacent the coal face where it is made fast to a suitable anchor or jack, and then by the winding of the drum 21 the machine is fed forward bodily on the track toward the face of the coal so that the cutting mechanism is thrust longitudinally into the vein. It will of course 80 be understood that if the construction shown in Figs. 1 and 2 is being used, the bracket arm 13 must be swung rearward from the position shown in dotted lines in Fig. 2 to 85 permit the entering cut to be made.

When the sumping cut has been completed, the bracket arm 13 having been made fast in its operative position (shown in full lines in Figs. 2, 3 and 4), the cable 23 is carried out around the guide pulley 25 and thence back to the machine and made fast to the hook 27. Then, the jacks 8 and 9 having been set to secure the machine firmly in position on the track, power is applied to the drum 21 to wind up the cable. The tension 90 of the cable, as will readily be understood, causes the bed plate 3 and all parts carried thereon to swing laterally from right to left, and this movement is continued until the extreme end of the cutter arm 6 is approximately in line with the left rib, the cutting mechanism having by its transverse movement formed a kerf extending horizontally across the front of the machine.

The jacks 8 and 9 having been taken down, 100 the cable can now be disengaged from the bracket 13 and used in a well known manner to feed the machine bodily away from the face thereby finishing the cutting of the kerf.

Heretofore it has been customary in handling machines such as hereinbefore described to effect the lateral swinging of the cutting mechanism by connecting the draft cable to an anchor or jack made fast adjacent the left rib toward which the cutting proceeds. The setting of such an anchor or jack consumes considerable time and unless it is set very securely, the machine operators are subjected to danger incident to the anchor giving way. With my improved bracket construction, it will be seen that I provide an abutment for the feed cable which is quite secure and which can be set in operative position quickly and easily.

While, as has been stated, the machine may be equipped for bracing purposes with the pair of jacks, it is to be understood that if it is made strong enough, the roof jack 5 may be omitted, and the machine held stationary during working solely by means of the side jack, and for the same reason, the latter jack may be also omitted if the weight and strength of the machine are sufficient.

10 In either instance, the shifting of the cutting mechanism is effected through the agency of the motor and windlass, the pivotally-mounted bracket being, of course, employed. As the construction just referred to is otherwise identical with that shown and described, additional illustration is obviously unnecessary.

I claim:—

1. In a mining machine of the type specified, the combination, with a truck, a bed-plate revolvably mounted thereon, and cutting mechanism and operating mechanism for the same mounted on the bed-plate for movement therewith; of a bracket pivotally 25 connected to said truck for movement into position at right-angles thereto; means for fastening said bracket in such position; a jack carried by said bracket for holding the truck stationary; and a windlass having 30 a driving connection with said operating mechanism, the cable of said windlass being connected at opposite ends with the windlass drum and the bed-plate and engaged intermediate its ends with said holding means, 35 to effect the rotation of said bed-plate.
2. In a mining machine of the character set forth, the combination of a truck frame, track wheels supporting the same, an elongated cutting mechanism carried by the 40 truck frame and extending horizontally therefrom, said cutting mechanism being mounted to swing laterally across the front

end of the truck, and means for effecting the said lateral movement of the cutting mechanism comprising a winding drum mounted 45 to move bodily with said mechanism, a bracket arm pivotally mounted on the truck frame, said bracket arm being adapted to swing from an inoperative position parallel to the longitudinal lines of the machine to 50 an operative position approximately at right angles to the longitudinal lines of the machine, means for securing the bracket arm in operative position, and a cable secured at one end to the winding drum and adapted 55 to extend to and be connected with the outer end of the bracket arm.

3. In a mining machine of the character set forth, the combination of a truck frame, track wheels supporting the same, an elongated cutting mechanism carried by the truck frame and extending horizontally therefrom, said cutting mechanism being mounted to swing laterally across the front 60 end of the truck, means for effecting the 65 said lateral movement of the cutting mechanism comprising a winding drum mounted to move bodily with the said mechanism, a bracket arm mounted on the truck frame and arranged to extend laterally and upwardly therefrom, a jack disposed upon the outer end of the bracket arm and adapted 70 to engage the roof of a mine, and a cable secured at one end to the winding drum and adapted to be connected with the outer end 75 of the bracket arm.

In testimony whereof I have hereunto set my hand in presence of two subscribing witnesses.

JONATHAN JENKINS.
